UNITED STATES PATENT OFFICE.

WALTER R. NOE, OF NEW YORK, N. Y.

PENCIL.

Application filed November 18, 1921. Serial No. 516,105.

To all whom it may concern:

Be it known that I, WALTER R. NOE, a citizen of the United States, and resident of New York, in the county of the Bronx and 5 State of New York, have invented certain new and useful Improvements in Pencils, of which the following is a specification.

My invention relates to mechanical pencils of the type in which the lead is advanced by the turning of the cap through screw threads within a removable sleeve such as is described in my application Number 478,633. It has for its object the provision of a concealed device to hold the 15 sleeve securely in place. The invention will be fully described hereinafter and the features of novelty will be pointed out in the appended claims.

In the enclosed drawings which are on 20 an enlarged scale and show an example of my invention without defining its limits, Figure 1 is a view of a pencil with my improved clip in place, Fig. 2 is a detail view, partly in elevation, of the improved part, 25 Fig. 3 is a longitudinal section on the line 3-3 of Fig. 2 and Fig. 4 is a cross section on the line 4-4 of Fig. 3.

As shown in the drawings the holding device is in the form of an improved clip. 30 I am aware that there is no novelty in the joint itself except through its connection with and concealment by the clip. It will be noted by reference to Fig. 2 that an opening 19 has been cut in the top of the barrel 35 10 and that a slot 18 extends from this opening. This opening and slot are concealed by the clip 20 which is soldered or otherwise fastened to the barrel in such a manner that its end is flush with the top of said barrel. 40 A shoulder 15 which is soldered or otherwise securely fastened to the sleeve 22 and which forms a false extension of the barrel, carries an extension 16 fitting tightly under the clip. A tongue 17 projects from 45 the extension 16 and when in place fits snugly in the slot 18. It is of course understood that the extension 16 may be omitted and the tongue 17 soldered separately to the sleeve, in which case the width of the opening 19 could be decreased. A raised piece 50 21 is also joined to the shoulder 15. It may be soldered to the shoulder or formed of the same metal or otherwise securely fastened. When in place this raised piece forms an 55 apparent extension of the clip 20.

When the pencil requires refilling the

sleeve is rotated downwardly in Fig. 2 by pressure in that direction on the raised piece 21 thus sliding the tongue 17 out of engagement with the slot 18. The cap 14 is then 60 pulled way from the barrel carrying with it all removable parts. This process is reversed when the parts are ready to be returned to the barrel with a new lead. The sleeve is inserted so that the extension 16 65 enters the opening 19. When the shoulder 15 comes flush with the barrel, the sleeve is turned in an upward direction in Fig. 2 by pushing over the raised piece 21 which then takes its place as an apparent part of the 70 clip while the tongue 17 engages the slot 18.

This device will securely hold the sleeve in position. It is inexpensive and will not affect the graceful lines of design.

The clip in addition to its normal functions not only conceals the opening and slot but by frictionally engaging at least the tongue 17, prevents the same from being unintentionally shifted out of the slot 18. 75

Various changes in the form shown and 80 described may be made within the scope of the claims without departing from the spirit of the invention.

I claim:

1. A pencil of the kind described comprising a barrel, mechanism within said barrel for advancing a lead and arranged to be withdrawn from said barrel to replenish the lead, co-operating means on said barrel and mechanism for locking same against separation and a clip mounted upon said barrel and concealing said co-operating means and engaging the same to prevent unintentional disconnection of said co-operating means. 85 90

2. A pencil of the kind described comprising a barrel provided with a recess, a clip mounted upon said barrel and concealing said recess, mechanism within said barrel for advancing a lead and arranged to be withdrawn therefrom to replenish the lead 100 and a tongue operatively connected with said mechanism and movable into said recess, said tongue being arranged to frictionally engage said clip and being held thereby against unintentional displacement whereby 105 separation of said mechanism from said barrel is resisted.

3. A pencil of the kind described comprising a barrel provided with an open ended slot and a transverse recess communicating therewith, a clip mounted upon said barrel and concealing said slot and recess, 110

mechanism within said barrel for advancing a lead, a shoulder connected with said mechanism and located externally of said barrel at one end thereof, and a tongue operatively combined with said shoulder and movable through said slot and into said recess to resist a separation of said shoulder from

said barrel, said tongue being arranged to frictionally engage said clip and being held thereby against unintentional displacement. ¹⁰

Signed at New York, in the county of New York and State of New York, this fifteenth day of Nov., A. D. 1921.

WALTER R. NOE.
